(57) CLAIM

The ornamental design for a vehicle or replica thereof, as shown and described.

DESCRIPTION

FIG. 1 is a rear left perspective view of a vehicle or replica thereof showing our new design;

FIG. 2 is a rear right perspective view of the design shown in FIG. 1;

FIG. 3 is a front right perspective view of the design shown in FIG. 1;

FIG. 4 is a front left perspective view of the design shown in FIG. 1;

FIG. 5 is a rear view of the design shown in FIG. 1;

FIG. 6 is a front view of the design shown in FIG. 1;

FIG. 7 is a right side view of the design shown in FIG. 1;

FIG. 8 is a left side view of the design shown in FIG. 1; and,

FIG. 9 is a top view of the design shown in FIG. 1.

The bottom of the vehicle or replica thereof forms no part of the claimed design. Additionally, the broken lines are for the purpose of illustrating portions of the vehicle or replica thereof and form no part of the claimed design.
